FORMING TRUING APPARATUS

Herbert A. Silven and Raymond A. Cole, Worcester, Mass., assignors to Norton Company, Worcester, Mass., a corporation of Massachusetts

Application February 14, 1939, Serial No. 256,320

2 Claims. (Cl. 125—11)

The invention relates to grinding machines, and more specifically to forming truing apparatus for the shaping of grinding wheels to a specific shape to grind work pieces to the complement of that shape.

One object of the invention is to provide a forming truing apparatus which is readily adjustable. Another object of the invention is to provide a forming truing apparatus including a form bar which is made up in sections whereby several shaped pieces may be used and placed close together or far apart by spacers. Another object of the invention is to provide a forming bar which may be used for a great length of time before it wears out. Another object of the invention is to provide a forming bar in the form of a surface of revolution whereby it may be indexed to bring new lines of the surface into contact with the follower to avoid the effects of wear. Another object of the invention is to provide a forming truing apparatus of long life and great flexibility of adjustment. Other objects will be in part obvious or in part pointed out hereinafter.

The invention accordingly consists in the features of construction, combinations of elements and arrangements of parts, as will be exemplified in the structure to be hereinafter described, and the scope of the application of which will be indicated in the following claims.

In the accompanying drawings illustrating one of many possible embodiments of the mechanical features of this invention,

Figure 1 is a front elevation of a grinding machine incorporating the forming truing apparatus of the invention;

Figure 2 is a view, partly in side elevation and partly in vertical axial section, of the forming truing apparatus, the section being taken along the line 2—2 of Figure 3;

Figure 3 is a front elevation of the forming truing apparatus;

Figure 4 is a horizontal sectional view, on an enlarged scale, of the form bar, the section being taken along the line 4—4 of Figure 3; and

Figure 5 is a hydraulic diagram.

Figure 1 illustrates in somewhat conventional form a cylindrical grinding machine. The forming truing apparatus of the invention may be applied to many different types of grinding machines but has particular utility in connection with cylindrical grinding machines. It may be applied to automatic grinders, but we herein disclose a hand operated grinding machine since the automatic features may be applied without interference with

the forming truing apparatus of the invention. As illustrated in Figure 1, the grinding machine may comprise a base 10 supporting for reciprocation or longitudinal adjustment a carriage 11 which supports a table 12 which may be fastened to the carriage 11 in various positions of angular adjustment, as is well known in the art. Adjustably fastened to the table 12 along ways 13 is a headstock 14 and also a tailstock 15. The headstock 14 may support a driving motor 16 adapted to rotate a face plate 17 through gearing contained in a gear casing 18 and a spindle 19 which is journaled in the headstock 14. Projecting from the face plate 17 is a work holding center 20 in line with and opposite a tail center 15 21 mounted in the tailstock 15. By means of a hand wheel 22 the tail center 21 may be advanced and retracted toward and from the head center 20, through the medium of screw means, not shown but well known. When the work piece W 20 has been centered in the machine, a lever 22 is used to clamp the tailstock 21 firmly in adjusted position.

For longitudinal adjustment of the carriage 11 there may be provided any suitable device, such as a hand wheel 25 having a pinion gear operating a spur gear 27 which is connected to a pinion gear 28 meshing with a rack 29 fastened to the under side of the carriage 11. The forming truing apparatus of the invention is chiefly used where the grinding is done by the so-called "plunge-cut" method, which involves no relative traverse between the grinding wheel and the work piece. Such a grinding operation will form the work piece to a complement or conjugate of the shaped grinding wheel. The hand wheel 25 is used to position the work piece W in the exact desired longitudinal position with respect to the grinding element in order to produce the shaped portion on the work piece in the desired position axially.

Still referring to Figure 1, we show a pair of grinding wheels 30 and 31 mounted on a single spindle, not shown, journaled in a wheel head 32, the grinding wheels being rotated by a motor 33 and suitable belting in a casing 34 connected to a pulley on the right-hand end of the wheel spindle. We have not shown the wheel spindle and wheel head in any more detail because any conventional drive and support for the grinding wheel may be used, such being well known in the art. In order that the wheels 30 and 31 may be fed transversely relative to the work piece W, there is provided a cross feed shaft 35 on which is mounted a ratchet 36 operated by a pawl 37 55

which is actuated by a cylinder piston hydraulic unit 38. Any other cross feeding mechanism may be substituted for that indicated.

We provide a massive wheel guard 40. This 5 wheel guard 40 is attached to the wheel head 32 and has a large opening 41 at the top bridged by a plate 42 having a smaller opening 43. Fastened to the wheel guard 40 on the upper side thereof, as is best shown at the left-hand side of 10 Figure 2, is a truing base 45. As shown, this base has an upwardly rising inclined web portion 46, a curved portion 47, a pair of bosses 48, and an upper plate portion 49. Still referring to Figure 2, longitudinally centrally disposed in the bottom 15 part of the curved portion 47 is a pivot pin 50. Pivotedly mounted on the base portion 45 by means of this pivot pin 50 is a slideway 51 receiving a cylinder 52. The angular adjustment in a vertical plane of the slideway 51 may be 20 effected by screws 53 whose lower ends engage shelves 54 integrally connected to the slideway 51. This adjustment is usually for minutes of arc only and in order to align the axis of the cylinder 52 with the axis of the wheels 30 and 31 more 25 accurately than can be done by machining operations on the various castings. However, the same result can be achieved by adjusting the table 12 on the carriage 11 to a like degree so far as results on the work piece are concerned.

30 The slideway 51 includes dovetailed portions 56 supporting a slide 57 which holds the dressing tool. The slide 57 is of generally hollow construction, as shown in Figure 2, and includes a hollow cylindrical portion 58 as well as dovetailed portions 59 fitting the dovetailed portions 56.

As indicated in dotted lines in Figure 3, a piston 60 is located in the cylinder 52 and has attached thereto a piston rod 61 fastened to a 40 plate 62 which extends rearwardly from the slide 57.

Referring now to Figure 2, the cylindrical portion 58 removably supports a sleeve 65 having at 45 the upper end and on the front thereof a shelf 66 and having opposite the shelf 66 at the rear thereof a boss 67 to which is fastened a follower member 68 by means of a bolt 69. The sleeve 65 is slidable vertically in the cylindrical portion 58 but lost motion is preferably eliminated by 50 means of a split bottom portion 70 of the cylindrical portion 58 controlled by a pull screw 71 and a push screw 72. See Figure 3 wherein the cover plate 74 of Figure 2 is removed. The shelf 66 fits between forked portions 75 of a member 55 76 attached to the upper part of the cylindrical portion 58 which prevents the sleeve 65 from turning in the cylindrical portion 58. The sleeve 65 is urged downwardly to keep the follower 68 in contact with the form bar hereinafter 60 described by means of a spring 80 fastened to a screw 81 in the shelf 66 and a screw 82 in a lug 83 projecting from the cylindrical portion 58. Merely by uncoupling the spring 80 and loosening the screw 71, the entire unit supported from 65 the sleeve 65 and including the follower 68 may be removed from the machine.

Supported in the upper end of the sleeve 65 is a bearing 90. This bearing is removable but may be firmly locked to the sleeve 65 as it fits 70 within a cylindrical bore thereof including split portions 91 which can be drawn together to clamp the bearing 90. A sleeve 92 is journaled in the bearing 90 and has keyed thereto the hub 93 of a spur gear wheel 94. The hub 93 is 75 mounted on an upper screw threaded portion

of the sleeve 92 and is locked on the sleeve 92 rigidly in a vertical direction by means of a pair of nuts 95 and 96. The sleeve 92 is internally threaded and fits on the upper threaded portion 97 of a quill 98 which is keyed by means of a key 99 to the sleeve 92.

Rotation of the gear 94 rotates the sleeve 92 which moves the quill 97 vertically in the sleeve 65, as relative rotation is prevented by the key 99. Positive downward movement can be effected because the sleeve 92 has a shoulder under the bearing 90, as shown. Angular movement of the spur gear 94 is for the purpose of adjusting the vertical position of the quill 98 in the sleeve 65; the sleeve 65 moves vertically in response to actuation of the follower 68 to generate the desired contour on the work piece. A dressing diamond 100 is embedded in a nib 101 fitting in a hole in the bottom of the quill 98 and retained therein by means of a screw 102.

For a delicate angular adjustment of the diamond by rotation of the spur gear 94, we provide a knob 105 on the bottom of a shaft 106 located in a vertical bearing 107 which is integral with a plate 108 fastened to the shelf 66. On the upper end of the shaft 106 is a pinion gear 110 meshing with the spur gear 94. A spring-pressed detent, not shown, located in a boss 111, enables the operator to feel the adjustment to a given tooth of the pinion gear 110 or spur gear 94.

In order to effect a dressing of the grinding wheels 30 and 31 or either of them, the dressing diamond 100 is moved in the general direction of the axis thereof by moving the slide 57 in response to movement of the piston 60 in the cylinder 52. As diagrammatically indicated in Figure 5, this may be achieved by a fluid pressure apparatus, such as a pump 115 connected to a suction pipe 116 drawing fluid out of a tank 117 and discharging the fluid into a piping 118 leading to a four-way valve 119 which may connect the fluid pressure to a pipe 120 or a pipe 121, depending upon the setting of the four-way valve 119, the other of these pipes being by the same valve connected to a return pipe 122 to 40 discharge the fluid into the tank 117, a pressure relief valve 123 being provided to govern the effective pressure of the fluid. The valve 119 may be manually or automatically controlled and when it is shifted, the slide 57 moves and causes 45 the diamond to dress the grinding wheels 30 and 31. Although the slide 57 moves rectilinearly, the diamond may be given an irregular motion in a vertical plane by a forming bar, now about 50 to be described, acting on the follower 68.

Referring now to Figure 2, attached to the upper plate portion 49 by means of screws 125, are a pair of supports 126 which are also shown, partly in section, in Figure 4. We provide a form bar spindle 127 which has a central axial 60 cylindrical bore with conical countersunk ends as shown in Figure 4. The form bar spindle 127 likewise has an enlarged head 130 at one end as shown. We provide a pair of hollow plugs 131 having conical end portions fitting the conical 65 countersunk ends of the bore in the spindle 127. We provide a central rod 135 which is threaded at both ends, and the rod 135, the plugs 131, and the spindle 127 are removably held together by means of nuts 136 on the rod 135. The rod 135 70 has a close fit in the plugs 131 but may have a loose fit in the spindle 127. The plugs 131 fit with a close fit in bores 137 in the supports 126. By means of the nuts 136 the plugs 131 can be 75 pressed into tight engagement with the spindle 75

127 and will hold it accurately centered. Therefore the spindle may be accurately located in the supports 126. For delicate axial adjustment and to locate the spindle 127 in exact desired position between the supports 126 we provide screws 140 and nuts 141, the screws 140 being in threaded engagement with and passing through the supports 126 and abutting the head 130 and a surface of revolution form bar mounted on the spindle 127.

10 As shown in Figure 4 we may provide a plurality of form bar members upon the spindle 127. As illustrated we have provided a form bar member 142 and a form bar member 143 separated by a spacer form bar member 144. The member 142 comprises a conical portion 142a and a cylindrical portion 142b. The form bar member 143 comprises a cylindrical portion 143a, a saddle-back anticlastic or pseudo-spherical surface of revolution portion 143b, and a conical portion 143c. The spacer 144 is cylindrical. All of the form bar members have a close fit upon the spindle 127 as shown. Preferably we provide set screws 145 in one of the form bar members, for example in the portion 142b of the form bar member 142, to hold the form bar members upon the spindle 127.

It will now be seen that the entire unit comprising the spindle 127 and all the form bar members and the plugs 131 may be removed as a unit from the machine simply by removing the screws 125, or the rod 135 may be removed from the spindle 127 and the form bar consisting of the spindle 127 and form bar members 142, 143 and 144 may be removed and replaced, if desired, with a differently shaped form bar. Furthermore by loosening the screws 140 the form bar may be rotated to bring a new portion thereof under the follower member 68. Thus after use of the machine for some time there is apt to be a little wear upon the form bar, but this need occasion no concern when using the form bar of the present invention for it may be readily rotated to bring a new unworn part of the form bar under the follower.

45 Another advantage of the present invention is the fact that two wheels 30 and 31 or any number of wheels, for that matter, may be shaped to predetermined shapes by form bar members, such as the members 142 and 143, and then spaced different distances apart which may be compensated for by using different sized spacers 144. In this way modifications of the work piece may be achieved with a very small change of the form bar. By providing a form bar built up of sections, a given shape on the grinding wheel or

grinding wheels can be quickly generated by selecting various mechanical, cylindrical, pseudo-spherical pieces for the form bar which may be kept in the tool room.

For the dressing of the grinding wheels the valve 119 is thrown into the opposite position from which it is found, either manually or mechanically, and this will cause oil to flow into the cylinder 52, moving the piston 60 and thereby moving the slide 57 which carries the diamond 100 as described. As the follower 68 moves along the form bar the sleeve 65 is raised and depressed in the cylindrical portion 58 to generate a shape on the grinding wheel or grinding wheels determined by the form bar.

15 It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

We claim:

1. In apparatus of the class described, a form bar comprising a hollow spindle, a plurality of form bar members on said spindle, each one having a surface of revolution, a central rod extending through the spindle, and plugs secured to the ends of the spindle by the central rod.

2. In apparatus of the class described, a dressing tool, means mounting the dressing tool for movement in a given direction, means mounting the dressing tool for movement in a direction transverse to the given direction, a follower controlling the second named movement of the dressing tool as it partakes of the first named movement, a pair of coaxial grinding wheels spaced apart in an axial direction, a form bar member positioned to be contacted by said follower having a contour the same as that of one of said grinding wheels, a second form bar member positioned to be contacted by said follower having a contour the same as that of the other of said grinding wheels, means to hold said form bar members together but not in contact with each other, a spacer separating the form bar members by the same distance that the grinding wheels are spaced, and a mounting for the assembly of the two form bar members the means to hold the two form bar members and the spacer.

HERBERT A. SIEVEN.

RAYMOND A. COLE.
